UNITED STATES PATENT OFFICE.

LIEBIE BORDEN, OF SPOKANE, WASHINGTON.

REFRIGERATOR.

Application filed June 28, 1920. Serial No. 392,457.

To all whom it may concern:

Be it known that I, LIEBIE BORDEN, a citizen of the United States, residing at Spokane, in the county of Spokane and State 5 of Washington, have invented a new and useful Refrigerator, of which the following is a specification.

The device forming the subject matter of this application is a refrigerator, and one 10 object of the invention is to provide novel means for supporting the ice in the refrigerator and to provide novel means whereby the filter pan may be removed readily. Another object of the invention is to provide 15 novel means for collecting the water from the melting ice and for storing the water for drinking purposes.

The device hereinafter described and claimed is an improvement on my prior 20 Patent No. 824,061 and it is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood 30 that, within the scope of what is claimed, changes in the precise embodiment of the invention shown can be made without departing from the spirit of the invention.

In the accompanying drawings:

Figure 1 shows in vertical section, a refrigerator constructed in accordance with the invention; Figures 2 and 3 are vertical sections taken through the refrigerator in 40 planes which are spaced horizontally from each other; Figure 4 is a horizontal section of the refrigerator; Figure 5 is a front elevation of the refrigerator; Figure 6 is a sectional detail showing one of the ventilating plugs; Figure 7 is an elevation showing a modification of the draw off cock for the water tank; Figure 8 is a section of one wall of a modified construction of a refrigerator.

The refrigerator forming the subject matter of this application includes a casing 1 having a lining 100 which, preferably, is made of enameled metal. Top closures 2 are hinged at 3 to the casing 1. Parallel walls 55 9 extend across the interior of the casing from the front of the casing to the rear

surface thereof. Between the walls 9 is located a tank 10. The tank 10 may be removed through an auxiliary door 11, located in the front of the casing 1 and held 60 in place by fastening devices 12. Water may be drawn from the tank 10 through a spigot 14 mounted in the door 11. A gauge glass 15 upstands from the spigot 14, exteriorly of the casing 1, and indicates the 65 amount of water in the tank 10. If desired, the gauge glass 15 may be removed from the spigot 14, and the opening formerly occupied by the glass may be closed by a plug 16 shown in Figure 7, the plug preferably 70 being threaded to cooperate with the boss 160, from which the gauge glass 15 has been removed.

A horizontal partition 4 extends across the lining 100 of the casing 1 and defines a provision compartment in the lower portion of the refrigerator. The numeral 17 designates a filter pan, the filter pan being supported on the floor 4 at an angle to the horizontal; the floor having a rib 107 which elevates a portion of the filter pan and disposes the same at an angle to the horizontal, as above set forth. The filter pan 17 may be removed through the door 5, hingedly mounted on the front of the casing 1. The 85 filter pan 17 is provided with an opening 6 in its bottom, the opening 6 discharging into a funnel-shaped pipe 20, the upper end of the pipe 20 being threaded into the horizontal partition 4, the lower end of the funnel pipe being threaded into the tank 10. A partition 21, which may be made of wire netting or other foraminous material extends across the filter pan 17 and defines two compartments, one of which is filled with 95 filtering material, designated by the numeral 22. The other compartment, indicated by the reference character 40, is empty, to allow a free passage of filtered water through the funnel pipe 20.

An ice tray 24 is disposed above the filter pan 17 and has a depression 25 provided with perforations 26, the perforations discharging into the filtering material 22 in the pan 17. A piece of corrugated metal 105 27 may be located in the tray 24 for the purpose of supporting the ice. The tray 24 is supplied with handles 28.

In order to ventilate the interior of the refrigerator, tubes 29 are mounted in the 110 casing 1 and in its lining 100. Plugs 30 are inserted into the tubes 29, each plug

having a bore 31 and lateral openings 32 communicating with the bore, each plug being supplied with a head 33 whereby the plug may be manipulated conveniently.

- 5 The plug 30 may be inserted into the tube 29 far enough so that all of the openings 32 are closed by the tube. Then, no air can leave the interior of the refrigerator by way of the tube and the plug. If, however, 10 plug 30 is pulled out to a slight extent, then certain of the perforations 32 will be placed in communication with the atmosphere, the arrangement being such that the air within the food compartment of the refrigerator 15 may escape.

The lining 100 is folded to form cleats 76 supporting the ice tray 24. Similar cleats 77 support the floor 4. The floor 4 and the bottom of the lining 100 are folded to form, 20 respectively, cleats 78 and 79, which retain the walls 9. The walls 9 and the lining 100 are folded to form cleats 81 supporting shelves 82 located in the provision compartment. Hooks 83 may be located in the provision compartment, in order that articles 25 may be suspended therein. Access is had to the provision compartment by way of doors 37 hinged at 38 to the casing 1.

In practical operation, when the ice in 30 the pan 24 melts, the resulting water passes into the depression 25 in the bottom of the ice pan and flows through the perforations 26 into the filtering material 22. The water follows the inclination of the filter pan 35 17 and passes into the compartment 40, the water leaving the compartment 40 by way of the opening 6 and entering the tank 10 through the funnel-shaped pipe 20. Water

may be drawn from the tank 10 at any time through the cock 14.

In Figure 8 there is shown a section of one wall of a modified construction of a refrigerator, and, therein, the lining has been designated by the numeral 100^a. The outer shell of the casing is denoted by the 45 numeral 100^b the elements 100^b and 100^a being separated to form an air space A. The lining may be in the form of a separate box, placed in the main body of the casing, Figure 8 rendering it evident that such a 50 construction may be resorted to.

Having thus described the invention, what is claimed is:

A refrigerator comprising a casing; a filter pan located in the casing and inclined 55 with respect to the horizontal; a tank located in the casing below the filter pan and having an outlet; a partition in the filter pan and defining compartments, one of which is filled with filtering material, the 60 other of which is located at the lowermost portion of the filter pan; means for establishing communication between the last specified compartment and the tank; and an ice pan supported in the casing above the 65 filter pan, the ice pan being provided at a point remote from said means with a perforated depression discharging into the filtering material.

In testimony that I claim the foregoing 70 as my own, I have hereto affixed my signature in the presence of two witnesses.

Mrs. LIBBIE BORDEN.
